COOKIE MOLD

Myron M. Levin, Lincolnwood, Ill.
(4315 N. Lincoln Ave., Chicago, Ill. 60618)

Filed July 20, 1967, Ser. No. 7,895

Term of patent 14 years

(Cl. D44—1)

FIG. 1

FIG. 2

FIG. 3.

FIG. 4.

FIG. 1 is a top plan view of a cookie mold showing my new design;

FIG. 2 is a right side elevational view;

FIG. 3 is a bottom plan view; and

FIG. 4 is an elevational view from the top of FIG. 1, as indicated by line 4-4 therein.

I claim:

The ornamental design for a cookie mold, as shown.
